UNITED STATES PATENT OFFICE.

MADISON F. BATES, OF LANSING, MICHIGAN.

INTERNAL-COMBUSTION ENGINE.

1,023,546.

Specification of Letters Patent.

Patented Apr. 16, 1912.

Application filed June 27, 1910. Serial No. 569,010.

To all whom it may concern:

Be it known that I, MADISON F. BATES, a citizen of the United States, residing at Lansing, in the county of Ingham, State 5 of Michigan, have invented certain new and useful Improvements in Internal-Combustion Engines; and I do declare the following to be a full, clear, and exact description of the invention, such as will enable others 10 skilled in the art to which it appertains to make and use the same, reference being had to the accompanying drawings, and to the characters of reference marked thereon, which form a part of this specification.

15 This invention relates to internal combustion engines, designed for using the heavier hydrocarbon fuels, and consists in the construction and arrangement of parts herein-after more fully set forth and claimed.

20 The object of the invention is to provide the piston of an explosive engine with a detachable or removable head to carry the packing rings whereby said head may be easily detached from the piston and removed 25 from the cylinder for the purpose of readily cleaning the rings from the usual accumulation of tarry matter which results from the use of kerosene and the heavier oils; the arrangement being such as to ob-

30 viate the necessity of disconnecting the connecting rod and removing the piston from the cylinder. The above object is attained by the structure illustrated in the accompanying drawings, in which:—

35 Figure 1 is a longitudinal section through the upper end of an engine cylinder showing a piston therein provided with my removable head carrying the packing rings, the connecting rod, and the base of the cylinder being broken away. Fig. 2 is a top plan of said removable head, a portion being broken away. Fig. 3 is a side elevation of said head, showing the circumferential grooves or channels therein in which the 40 rings lie. Fig. 4 is a plan view of the end of the piston. Fig. 5 is an elevation of the piston with the removable head secured to the end thereof and showing the piston rings within the grooves of said head.

45 Referring to the characters of reference, 1 designates the cylinder of an explosive engine having therein a piston 2 connected by the connecting rod 3 with the crank shaft, not shown. The piston is open

55 at its ends, as shown, the aperture 4 in the upper end being of lesser diameter than the interior of the piston, thereby forming at the upper end of the piston a diametrically extending flange 5.

60 The head 6 of the piston is in the form of a hollow cap having the circumferential grooves 7 in which the expansion packing rings 8 lie. Surrounding the opening 9 in the piston head is an annular flange 10 adapted to enter the opening 4 in the end 65 of the piston and position said head thereon. Formed in the wall of the head of the piston are the ribs or beads 11 which are provided with apertures 12 adapted to receive the bolts 13. The lower end of said bolts 70 are threaded to screw into the tapped apertures 14 in the flange 5 at the end of the piston, which flange at that point is made thicker, as shown by dotted lines 15 in Fig. 4, to afford a firmer anchorage for said bolts. 75 The upper end of the bolts 13 receive the nuts 16 which screw against the upper face of the piston head 6, whereby said head may be securely fastened to the end of the piston in a manner to enable it to be readily detached for removal, when desired. The hollow head 6 lightens the weight of the piston and obviates the liability of overheating.

80 In explosive engines driven by the combustion of kerosene, or other oils rich in carbon, it has been found that the packing rings become clogged with a tarry substance, the removal of which has heretofore necessitated the withdrawal of the piston from the cylinder, involving the disconnecting 85 of the connecting rod. By providing the piston with a removable head which carries the packing rings, it is only necessary to remove said head to enable the rings to be thoroughly cleaned, access to the piston 90 head being obtained by removing the head 17 of the cylinder, when by loosening the nuts 16, the piston head 6 with the packing rings 8 may be easily withdrawn. Said piston head may be readily replaced after the 95 packing rings have been cleaned by sliding it into position over the bolts 13 and tightening the nuts 16.

100 Having thus fully set forth by invention, what I claim as new and desire to secure by Letters Patent, is:—

105 In an explosive engine, a hollow piston having an opening therethrough and

provided at its upper end with a diametrically extending flange, a hollow packing head closed at its outer end, and having at its inner end an annular flange
5 adapted to fit within the diametrical flange of the piston, said head having circumferential grooves and packing rings within said grooves, bolts passing through the packing head and into the diametrical

flange at the end of the piston, and nuts 10 upon said bolts engaging the packing head.

In testimony whereof, I sign this specification in the presence of two witnesses.

MADISON F. BATES.
